UNITED STATES PATENT OFFICE.

JOSEPH JANCEK, OF NEW YORK, N. Y.

TOY.

1,334,954.

Specification of Letters Patent.

Patented Mar. 30, 1920.

Application filed October 15, 1919. Serial No. 330,745.

To all whom it may concern:

Be it known that I, JOSEPH JANCEK, a citizen of the United States, and a resident of the city of New York, borough of Manhattan, county of New York, and State of New York, have invented certain new and useful Improvements in Toys, of which the following is a full, clear, and exact specification.

10 My invention relates to toys, and its object is to provide a novel device of this class in which a steel ball, once started on its course, makes a series of leaps over properly arranged troughs and posts. A preferred 15 form of construction is illustrated in the accompanying drawing in which—

Figure 1 is a plan view;

Fig. 2 shows a longitudinal section on line 2—2 of Fig. 1, and
20 Fig. 3 is a transverse section on line 3—3 of Fig. 3.

The base 1, which may be of wood or other suitable material, has mounted thereon a series of standards 2, 3, 4, 5 and 6. There 25 are five standards in this instance, but the number may vary. Each standard consists of two sections, a lower fixed section 7 and an upper section 8 slidably mounted on the lower section. A set-screw 9, carried by the 30 lower section 7 of each standard, clamps the upper section in any adjusted position. Any other suitable arrangement may be resorted to for adjusting the heights of the standards.

The standards 2, 3, 4, 5 and 6 carry at 35 their upper ends the troughs 10, 11, 12, 13 and 14, respectively. The standards are so adjusted that these troughs are held at gradually decreasing heights, trough 10 being the highest and trough 14 the lowest, as shown 40 in Fig. 2.

Arranged in line with the troughs are the flat-top posts 15, 16, 17 and 18, which are rigidly mounted on the base 1. These posts may be of steel, glass or other hard elastic 45 material, and are of approximately the same height. As seen from Fig. 2, the posts are lower than the lowest trough 14.

The relative arrangement and adjustment of the troughs and posts are such that a 50 small steel ball (or one made of other hard elastic material), when dropped or placed in the trough 10, will automatically follow the course roughly indicated by the dotted line J in Fig. 2. That is to say, the ball B 55 will drop onto the post 15, and from there

rebound into the trough 11; from the trough 11 it will drop onto the next post 16, rebound into the trough 12, and so on, leaping over the succeeding troughs and posts until it falls into the tray 19. This receiving tray may be a separate receptacle, or merely a shallow recess cut in the base 1, as illustrated. If desired, the tray 19 may have a series of numbered pockets suitably arranged, into which the balls may roll.

To catch any balls that may not reach the tray 19, the base 1 is provided with the longitudinal channels or runways 20 which slope downwardly toward the recess 21, into which the balls will roll from either 70 channel. The central section 22 of the base is preferably formed to slope toward the channels 20, so that any ball which drops onto the section 22 will roll into one of the channels 20, whence it gravitates into the recess 21. The base 1 may be provided with suitable means for adjusting it with respect to the horizontal. For this purpose I have shown a pair of screws 23 provided with knurled heads 24, for readily turning the 75 screws until the base is in the right position.

I have obtained the most satisfactory results with posts of hard steel, and I found that it is best to use posts of increasing hardness. That is to say, if the post 15 is of 85 mildly tempered steel, the post 16 should be a little harder (at least at the top), and so on, the last post 18 being glass-hard. After each upward leap or rebound, the ball loses some of its momentum, so that when it 90 drops from the trough 13 onto the post 18, it is so weak (as it were) in its velocity that it must strike a very hard surface to be lifted by the rebound into the trough 14.

With balls of different weights or different material, the heights of the troughs will, of course, have to be adjusted to suit each particular ball or set of balls. Even balls of the same material and of apparently the same size, shape and weight, do not behave in exactly the same way, and this uncertainty serves to increase the fascination of the toy.

While I have shown and described a particular construction, I do not wish to be limited to the details herein set forth, because it is obvious that the basic idea of my invention may be mechanically carried out in other ways.

Having thus described my invention 110

which I claim as new and desire to secure by Letters Patent of the United States, is:

1. A toy comprising a base, a series of spaced troughs supported in alinement on said base at gradually decreasing heights, and a flat-topped upright post of hard elastic material fixed upon said base between each pair of adjacent troughs and in alinement therewith, said posts being lower than said troughs, the relative heights and spacing of said troughs and posts being such that a hard elastic ball placed or dropped in the highest trough will fall upon the adjacent post, whence it will rebound into the next trough and from there fall upon the next post, this action of the ball being automatically repeated for the successive posts and troughs.
2. A toy comprising a base, a series of spaced troughs supported in alinement on said base at gradually decreasing heights, and a flat-topped upright post of hard elastic material fixed upon said base between each pair of adjacent troughs and in alinement therewith, said posts being lower than said troughs, the relative heights and spacing of said troughs and posts being such that a hard elastic ball placed or dropped in the highest trough will fall upon the adjacent post, whence it will rebound into the next trough and from there fall upon the next post, this action of the ball being automatically repeated for the successive posts and troughs, and means for regulating the height of each trough.
3. A toy comprising a base, a series of spaced standards mounted in alinement on said base, each standard consisting of a fixed lower part and a vertically adjustable upper part, a trough carried by the upper part of each standard, said troughs being supported at gradually decreasing heights, and a flat-topped upright post of hard elastic material fixed upon said base between each pair of adjacent troughs and in alinement therewith, said posts being lower than said troughs, the relative heights and spacing of said troughs and posts being such that a hard elastic ball placed or dropped in the highest trough will fall upon the adjacent post, whence it will rebound into the next

trough and from there fall upon the next post, this action of the ball being automatically repeated for the successive posts and troughs.

4. A toy comprising a base, a series of spaced troughs supported in alinement on said base at gradually decreasing heights, and a flat-topped upright post of steel fixed upon said base between each pair of adjacent troughs, said posts being lower than said troughs and the top surface of each post increasing in hardness from the post between the two highest troughs to the post between the two lowest troughs, for the purposes set forth.

5. A toy comprising a base, a series of spaced troughs supported in alinement on said base at gradually decreasing heights, and a flat-topped upright post of steel fixed upon said base between each pair of adjacent troughs, said posts being lower than said troughs and the top surface of each post increasing in hardness from the post between the two highest troughs to the post between the two lowest troughs, for the purposes set forth, and means for regulating the height of each trough.

6. A toy comprising a base, a series of spaced troughs supported in alinement on said base at gradually decreasing heights, and a flat-topped upright post of hard elastic material fixed upon said base between each pair of adjacent troughs and in alinement therewith, said posts being lower than said troughs, the relative heights and spacing of said troughs and posts being such that a hard elastic ball placed or dropped in the highest trough will fall upon the adjacent post, whence it will rebound into the next trough and from there fall upon the next post, this action of the ball being automatically repeated for the successive posts and troughs, said base having a pair of longitudinal channels or runways to receive any ball that fails to rebound into a trough, said base being also provided with a tray to receive the balls that drop from the last or lowest trough.

In witness whereof, I hereunto subscribe my name this 8 day of October, 1919.

JOSEPH JANCEK.
